INDEX CARD IN SELECTIVE CARD-SORTING SYSTEM

Albert A. Rembold, San Francisco, Calif.

Application November 5, 1948, Serial No. 58,496

3 Claims. (Cl. 129—16.1)

1

This invention relates particularly to index cards used in selective card sorting systems of the type generally shown in my United States Letters Patent No. 2,198,127, of April 23, 1940, and in earlier card systems such as United States Letters Patent No. 1,739,087, of December 10, 1929, to Perkins.

Cards of the above type are formed with coded openings formed in one or more marginal portions thereof, the openings being in one or more rows extending parallel with the adjacent edge of each card. By slotting out certain of the openings to said edge, while leaving others unslotted, a large number of different combinations of slotted and unslotted openings may be made. When cards formed to provide these combinations are arranged in a horizontal row with the corresponding openings in registration, the removal of desired cards from the row is effected by thrusting one or more needles through one or more of the registering openings. When more than one needle is used, they are thrust through combinations of the coded openings. By elevating the horizontally elongated needles one or more cards will be released from the row and others will be suspended from the needles.

Several methods of sorting are employed, but the physical operation of thrusting the needles through registering openings and then elevating the needles, is common to all.

Most cards used in selective sorting systems are marginally punched along several of the edges, and in most of said systems, there are index cards that divide the rows into various sections or divisions. These index cards may have an upper upstanding tab or margin that is visible to the operator, and on which the data or datum identifying a division or section appears.

In the sorting operation, one or several subdivisions may be in a drawer or support, and groups of the cards in amounts that are conveniently sorted may be placed in a sorting tray or the like, where they are aligned and the needles inserted to effect a release of the desired cards when the needles are elevated.

Heretofore, it has been customary to remove the index cards, when the cards are inverted to position their lower edges uppermost for a sorting operation in which the marginally punched and slotted openings along the lower edge of the cards is used. The reason for this is that when the upstanding tabs on the index cards are lowermost, and rest on the bottom of the sorting tray, the remaining cards will shift downwardly so as to also be supported on the bottom. Thus, any

2

openings for any purpose that might have been punched in the index cards that might register with the openings in the remaining cards when the cards are upright before inversion, would be covered by a blank area on the index cards and the needles would be obstructed from passing through the cards, although I know of no such openings having heretofore been provided in index cards.

10 One of the objects of this invention is the provision of index cards in a card sorting system of the character described in which said cards may remain in the row of cards at all times without obstructing the passage of the needles.

15 Other objects and advantages will appear in the description and in the drawings.

In the drawings,

Fig. 1 is a side view of one of the index cards of this invention in its normal upright position.

20 Fig. 2 is a fragmentary isometric view of several cards in a selective card sorting system that includes one index card in its normal upright position, all of said cards being on several sorting needles, and the cards being spaced apart slightly for clarity.

Fig. 3 is a view similar to that of Fig. 2, but one in which the cards are inverted. The same cards are shown in said view as in Fig. 2, but only one needle is illustrated.

30 In detail, the index card is indicated at 1, and other cards of the system are designated 2.

Cards 2 are customarily punched out along their margins to form marginally punched openings 3, 4 respectively along the upper and lower edges of the cards 2, and marginally punched openings 5, 6 respectively along the upper and lower edges of the index cards 1 have not heretofore been provided in index cards, but may be formed in carrying out this invention. The opposite vertically extending marginal portions of all of the cards may be punched in the same manner as is shown.

40 As a result of the above operation, when a row of cards is in the drawer or sorting tray, the tabs or upper margins 7 of the index cards 1 will be elevated above the remaining cards in the row, and the identifying letters, numbers or symbols 8 on said tabs will be visible.

When the cards are inverted so as to perform 50 the sorting operation in which the openings 4 in the cards 2 are used, it will be obvious that all of the cards 2 will move downwardly relative to index cards 1 so that their lowermost edges will be supported on the tray. This movement will 55 cause the openings 4 to move out of registration

with the openings 6 in the index cards and the needles 9 (Figs. 2, 3) would be stopped by the blank marginal portions of the index cards to prevent the sorting operation, unless some provision were made to enable the needles to pass.

Provision for passing the needles is made by forming openings 10 in cards 1 that are adjacent openings 6 but which openings will register with the openings 4 in cards 2 when the cards are inverted. By this structure, it will be seen that the openings 6 will register with openings 4 when the cards are upright, and openings 10 will register with openings 4 when the cards are inverted and when the lower edges of the inverted cards 1, 2 are in alignment. Heretofore, insofar as I am aware, index cards have never been formed with marginally punched openings along their lower edges that are adapted to register with the marginally punched openings along the lower edges of other cards, such as cards 2, irrespective of whether the cards are upright or inverted.

It is to be understood that when the front side of the sorting tray (not shown) is left open, an operator may insert the sorting needles through the lowermost openings 6 in the index cards and then swing the needles so that the slots extending from the openings in the lowermost row are uppermost for releasing the cards. In this operation the index cards do not have to be removed, but the step is so awkward and difficult that most operators might consider it preferable to remove the index cards before sorting in order to prevent possible injury to the margins 7 that would project below the row after inversion of the cards, should the row of suspended cards be dropped onto a table. Neither openings 6, nor 10, nor 5 have heretofore been provided.

The provision whereby the openings 10 will register with openings 4 when the cards are inverted thus eliminates the necessity for trying to invert the cards when the sorting needles are in the openings, although the operator may use that system by employing openings 6, if so desired, and it also eliminates the necessity for removing the index cards should the operator wish to lay the inverted row of cards on the bottom of the tray, or table. However, the operator may still employ the first system mentioned, if he or she so desires, which heretofore has not been possible, insofar as I am aware.

The term "tab" used herein is not to be restricted to a limited portion of an index card along its upper edge, but is intended to constitute either such portion or the entire upper marginal portion of each card that projects above the remaining cards in the row.

The data bearing cards, such as cards 2, will be called "data" cards in the claims to distinguish them from the "index" cards.

I claim:

1. In a selection card system that includes vertically disposed data cards of the same shape and size formed with corresponding marginally punched coded openings in rows extending along the upper and lower edges respectively of said data cards, said cards being in a row with their openings in registration with each other and with their upper and lower edges in alignment in direction longitudinally of said row of cards,

an index card in said row having its lower edge in alignment with the other cards of said row and having a tab projecting upwardly above said row, a first row of openings formed in said index card spaced from said tab and positioned to register with the openings of the upper row on said data cards, a second row of openings formed in said index card along its lower edge positioned to register with the lower openings in said data cards when said data and index cards are inverted with their upper edges lowermost and in alignment longitudinally of said row of cards.

2. In a selection card system that includes vertically disposed data cards of the same shape and size formed with corresponding marginally punched coded openings in rows extending along the upper and lower edges respectively of said data cards, said cards being in a row with their openings in registration with each other and with their upper and lower edges in alignment in direction longitudinally of said row of cards, an index card in said row having its lower edge in alignment with the other cards of said row and having a tab projecting upwardly above said row, a first row of openings formed in said index card spaced from said tab and positioned to register with the openings of the upper row on said data cards, a second row of openings formed in said index card along its lower edge positioned to register with the lower openings in said data cards when said data and index cards are inverted with their upper edges lowermost and in alignment longitudinally of said row of cards.

3. In a selection card system that includes vertically disposed data cards of the same shape and size formed with corresponding marginally punched coded openings in rows extending along the upper and lower edges respectively of said data cards, said cards being in a row with their openings in registration with each other and with their upper and lower edges in alignment in direction longitudinally of said row of cards, an index card in said row having its lower edge in alignment with the other cards of said row and having a tab projecting upwardly above said row, a first row of openings formed in said index card spaced from said tab and positioned to register with the openings of the upper row on said data cards, a second row of openings formed in said index card along its lower edge positioned to register with the lower openings of the lower rows of openings in said data cards when the lower edges of said data and said index cards are in alignment longitudinally of said row of cards.

4. In a selection card system that includes
